PATENTED DEC. 25, 1906.

F. C. ANDERSON.
SWITCH INTERLOCKING MECHANISM.
APPLICATION FILED DEC. 30, 1905.

UNITED STATES PATENT OFFICE.

FRANK C. ANDERSON, OF CINCINNATI, OHIO, ASSIGNOR TO THE AMERICAN VALVE & METER COMPANY, OF CINCINNATI, OHIO, A CORPORATION OF WEST VIRGINIA.

SWITCH-INTERLOCKING MECHANISM.

No. 839,089.

Specification of Letters Patent.

Patented Dec. 25, 1906.

Application filed December 30, 1905. Serial No. 293,975.

To all whom it may concern:

Be it known that I, FRANK C. ANDERSON, a citizen of the United States, residing at Cincinnati, in the county of Hamilton and State of Ohio, have invented certain new and useful Improvements in Switch-Interlocking Mechanism, of which the following is a specification.

My invention relates to means for insuring safety in the use of railway-switches, the object being to render it impossible to lock a switch until the point-rail has been brought against the stock-rail.

My invention consists of the combination, with a switch-stand, of a plunger adapted for entering an opening in an interlocking-bar in said switch-stand when the switch is properly closed and of a connection to said plunger so arranged as to prevent the locking of said switch-stand when the switch is not properly closed.

My invention also consists of the parts and combination and arrangement of parts as set forth and claimed.

In the drawings, Figure 1 is a plan of a switch and stand having my invention applied thereto. Fig. 2 is an elevation of the interlocking-bar. Fig. 3 is an elevation of the elbow. Fig. 4 is a perspective view of a modification of the elbow. Fig. 5 is a cross-section of the switch-stand. Fig. 6 is a perspective view of the bell-crank. Fig. 7 is a perspective view of the horizontal plunger-head. Fig. 8 is a perspective view of the plug. Fig. 9 is a perspective view of the horizontal plunger. Fig. 10 is a perspective view of the vertical plunger. Fig. 11 is a vertical section on the line $x-x$ of Fig. 1. Fig. 12 is a similar view of the switch-stand in unlocked position. Fig. 13 is a perspective view of the connecting-rod. Fig. 14 is a perspective view of the connecting-rod head. Fig. 15 is a perspective view of the shield.

I prefer to construct my improved switch-interlocking mechanism as follows: The switch-stand 1 has the top plate 2 and vertical shaft 3, which is connected, by means of the crank 4 and bars 5 and 6, to the point-rail 7 of the switch. The shaft 3 is rotated to throw the switch by means of the handle 8, which is hinged vertically at 9 and has the lug 10, adapted to engage within the slots 11 or 12 to hold the switch open or closed. The

lug 10 has an opening 13, so that a lock 14 may be used to secure it in the desired position. Contiguous to the slot 11 is an opening 15, through which the vertical plunger 16 may extend upwardly and engage the handle 8. This plunger 16 is supported by the elbow 17, into which it fits loosely, the elbow 17 being supported on the upper end of the connecting-rod 18. A housing 19 of suitable form is supported on the base 20 of the switch-stand 1, and a bell-crank 21 is journaled horizontally therein on the pin 22. A head 23 on the lower end of the connecting-rod 18 is pivoted to one of the arms 24 of the bell-crank 21, and the horizontal plunger 25 is screwed into another head 26, which head is pivoted to the other arm 27 of the bell-crank 21. The connecting-rod 18 has a sliding bearing 28 in the top of the housing 19, and the plunger 25 has a similar bearing 29 in a rib 30 of the housing 19. The movement of the mechanism is limited in one direction by the shoulder 31 on the plunger 16 engaging the lower side of the top plate 2 and in the other direction by the shoulder 32 on the plunger 25 engaging the rib 30. Between the rib 30 and the head 26 is interposed the spring 33, coiled around the plunger 25.

The interlocking-bar 34 is slidably mounted in the portion 35 of the housing 19 and is bent downward at 36 and suitably connected to the dog 37, which embraces the guard 38 on the point-rail 7. This interlocking-bar 34 has an opening 39 at such a point and of such shape that the plunger 25 can enter it only when the point-rail 7 has been drawn closely against the stock-rail 40.

Since it is necessary for the plunger 25 to enter the opening 39 before the handle 8 can be locked down, as shown in Fig. 11, it is obviously impossible to lock the switch-stand until the point-rail 7 has been brought closely against the stock-rail 40, thus effectually closing the switch. In opening the switch, as soon as the handle 8 is released the spring 33, acting through the series of connections, throws the handle 8 upward and draws the plunger 25 out of the opening 39, permitting the switch to be opened.

In order to allow my invention to be used on a switch-stand in either right or left position, a second opening 41 is provided contiguous to the slot 12 in the top plate 2 and a sec-

ond opening 42 is provided in the interlocking-bar 34. Then the elbow 17 may be swung around on the connecting-rod 18, so that the plunger 16 may enter the opening 41. The opening 42 in the interlocking-bar 34, however, is placed a greater distance from the opening 39 than the throw of the switch amounts to in order that the switch may not be locked open, and in order to 5 adapt my invention for both right and left positions I further provide the turnbuckle 43 in the connection between the interlocking-bar 34 and the dog 37, thus making it possible to adjust the interlocking-bar 34 so that 10 the opening 42 will be in the proper position to receive the plunger 25 when the right-hand switch is closed. This of course would throw the opening 39 out of position, rendering it impossible to lock the switch in the opposite position. 15

Where it is desirable that the switch may be interlocked in either open or closed position, as is the case at the end of a double track or crossover, a modification 17^a of the 20 elbow 17 may be used, having the two arms 44 and 45, each of which would carry a plunger like the plunger 16, extending into both the openings 15 and 41. When the above modification is used, the openings 39 and 42 25 in the interlocking-bar 34 are placed a distance apart equal to the throw of the switch, thus allowing the plunger 25 to enter one of them when the switch is either in open or closed position and permit the handle 8 to be locked into either position. Where it is 30 deemed necessary to prevent the locking of the switch in either one of the positions, I provide a shield 46 to be fastened adjacent to one of the slots by means of bolts passing 35 through holes 47 in the top plate 2 and holes 48 in the shield-closing hole 13 in handle 8 to prevent inserting of padlock 14 or other means. In order to facilitate the removal of the plunger 16 from the elbow 17 or its adjustment therein, I prefer to support it by 40 means of the plug 49, screwed into the elbow 17 under the plunger 16. The adjustment of the plunger 16 by plug 49 takes up any wear causing lost motion in the interlocking 45 mechanism between the operating-handle of the switch-stand and interlocking-bar. The 50 holes 50 and 51 in the crank-arms 24 and 27 are sufficiently larger than the pins 52 and 53 to allow the rod 18 and plunger 25 to move 55 in straight lines when the mechanism is operated, and the rod 18 is further secured into the head 23 by means of a rivet passing through holes 54 and 55 in the head 23 and rod 18, respectively. My invention is equally 60 valuable for insuring the proper closing of the switch whether the danger consist in an obstruction between the point-rail 7 and stock-rail 40 or whether it be a disconnection—such, for instance, as the falling out 65 or intentional removal of the pin 56 in the

rods 5 and 6. In either case the interlocking-bar would not be moved into a position allowing the plunger 25 to enter the opening 39 or 42, as the case might be, and in the latter instance the switch could be operated 70 temporarily by means of the interlocking-bar 34. For this purpose I provide the handle 57 on the end thereof. I also provide a guide 58 for said bar, which guide is secured to the cross-tie 59, as shown. The casing 19 75 is secured to the base 20 by means of bolts 60 passing through the holes 61 in the base.

While I have shown and described a peculiar construction herein, I do not wish to be understood as limiting myself to it; but 80

What I desire to secure by Letters Patent is—

1. In a switch-interlocking mechanism, an interlocking-bar connected to the point-rail of a switch and having an opening in said bar, 85 a plunger adapted to enter said opening, a bell-crank adapted to throw said plunger, a connecting-rod adapted to actuate said bell-crank, an operating-handle and means for engaging said handle and connecting-rod to engage or disengage said plunger and interlocking-bar.

2. In a switch-interlocking mechanism, an interlocking-bar having an opening, an operating-handle, an adjustable plunger engaging 95 said handle, a plunger adapted to engage within said opening and a connection between said plungers whereby said handle cannot be secured stationary except when said plunger is in said opening. 100

3. In a switch-interlocking mechanism the combination with a switch-stand having a vertical shaft and a vertically-disengageable handle, of a vertical plunger, a connecting-rod operatively connected to said plunger, a 105 casing in which said connecting-rod is slidably mounted, a bell-crank mounted in said casing and pivotally connected to said connecting-rod, a horizontal plunger pivotally connected to said bell-crank and slidably mounted in 110 said casing, a spring acting to hold said vertical plunger against said handle and an interlocking-bar connected to the point-rail of a switch and having an opening adapted to admit said horizontal plunger substantially as 115 and for the purpose specified.

4. In a switch-interlocking mechanism the combination with a switch-stand having a vertical shaft and a vertically-disengageable handle and means for locking said handle, of a vertical plunger engaging said handle, a supporting-elbow therefor, a connecting-rod upon which said elbow is pivotally supported, a casing in which said connecting-rod is slidably mounted, a bell-crank mounted in said 120 casing, a horizontal plunger slidably mounted in said casing, pivotal connection between said bell-crank and said connecting-rod and between said bell-crank and said horizontal plunger, an interlocking-bar slidably mount- 125

ed in said casing having an opening, a connection between said interlocking-bar and the point-rail of a switch whereby said opening is adapted to receive said horizontal plunger only when said point-rail is in properly-closed position, a top plate on said switch-stand having openings adapted to receive said handle and openings adjacent thereto through which said vertical plunger may engage said handle substantially as and for the purpose specified.

5. In a switch-interlocking mechanism, an interlocking-bar having an opening, an operating-handle, a plunger engaging said handle, a plunger engaging within said opening and a connection between said plungers whereby said handle cannot be secured stationary except when said plunger is in said opening.
